Philadelphia, Pa.

Application April 7, 1938, Serial No. 200,594

4 Claims. (Cl. 273—102)

This invention relates to targets such as are commonly employed for receiving and retaining pointed missiles, the points of which are imbedded in the target.

In the playing of the various games such as those involving the throwing of darts at a target, it is essential in every instance that the pointed dart strike the target with sufficient force for the point to become imbedded therein and retain its position so that it may be observed where the dart has struck.

At the present time it is substantially the universal practice to employ as the main body of the dart board a wooden structure, either laminated or otherwise, and which wooden construction is adapted to have the dart points imbedded therein. However, after continued usage of the dart board, which involves the striking of the darts thereagainst many times, the surface against which the darts strike becomes damaged and worn to such an extent as to finally render the dart board substantially unless and entirely unsatisfactory for the playing of any of the games of darts thereon.

With the foregoing conditions in mind, this invention has in view, as its foremost objective, the provision of a target which includes a laminated main body part that is made up of a plurality of thin layers of material which are arranged in a compact manner so that the edges of the layers define a continuous unbroken target surface. With this surface defined by such a plurality of tightly assembled edges, a point of a dart striking thereagainst will pass between two of the thin layers and assume its imbedded position. When the point is withdrawn adjacent layers will return to their usual compact relationship.

More in detail this invention has in view, as an objective, the provision of a target including a main body part made from a plurality of strips in the manner aforesaid, in which the strips are assembled with a proper degree of tightness to, in the first instance, present substantially a smooth unbroken surface as the target, and yet be sufficiently loose to permit a certain amount of spreading as the dart point is imbedded therein.

At the present time there is available to the public a type of dart board which is meeting with widespread approval. This type of dart board comprises a rectangular framework which is formed with a large circular opening in which is received the main body part of the dart board. The framework surrounding the opening is divided into appropriate divisions bearing num-

bers, and the position of the central main body part may be varied with respect to these numbers, there being means provided to maintain the central part assembled in the framework.

In view of the circular construction of the main body part in this type of dart board, the invention has in view, as a further object, the provision of a dart board in which the main body part is of circular formation and which comprises a strip of material which is spirally and tightly wound into the circular formation required. Obviously the edges of the spirally wound strip define the target surfaces of the dart board.

Another object of the invention is the provision of a dart board including a main body part which is formed from a strip or strips of paper.

Yet another object in view is the provision of a dart board of the character above noted, including a circular main body part made up of a strip of material spirally wound into the circular shape and presenting a target surface defined by the edge of said strip, said target surface being provided with appropriate markers dividing the main body part into sections in accordance with conventional practice in this art.

It is now well recognized in the art of dart boards that metallic devices such as steel wire should be employed for the purpose of marking off the target surface, because with markers of this type a dart assumes a position on one side or the other of the line defined by the marker and cannot become imbedded on the line.

Further and more particular objects of the invention are associated with the provision of means incorporating these metallic markers into the main body part in the manner aforesaid.

These and other features and advantages will in part become apparent, and in part be herein-after stated, as the description of the invention proceeds.

The invention, therefore, comprises a dart board including a laminated main body part made from a strip or strips of material, preferably paper, which is compactly arranged so that the edges of the strip define continuous unbroken target surfaces of the dart board. The strip is preferably spirally and tightly wound, and the target surfaces are provided with metallic markers in accordance with conventional practice.

For a full and more complete understanding of the invention reference may be had to the following description and accompanying drawings, wherein

Figure 1 is an elevational showing of a dart board embodying the precepts of this invention,

Figure 2 is a horizontal section taken about on the plane represented by the line 2—2 of Figure 1,

Figure 3 is an enlarged fragmentary showing in elevation of a section of the dart board,

Figure 4 is an enlarged detail view in perspective of a ring element employed at the center 10 of the dart board,

Figure 5 is a similar perspective view of several turns of the strip,

Figure 6 is an elevational showing of a portion of a metallic ring included in the main body part,

Figure 7 is an elevational showing of a modified form of dart board,

Figure 8 is a side elevational showing of the form shown in Figure 7,

Figure 9 is an enlarged fragmentary view of 20 a portion of the dart board shown in Figure 7, and

Figure 10 is an enlarged detail view in perspective, bringing out the disposition of the turns of the strip making up the dart board shown in 25 Figure 7.

Referring now to the drawings, wherein like reference characters denote corresponding parts, a target such as a dart board is shown in Figure 1 as comprising rectangular framework 10 30 which may be made from any appropriate material such as wood. The framework 10 is formed with a large circular opening 11 which is designed to receive the main body part of the dart board. This main body part is referred 35 to in its entirety by the reference character B, and is shown as being of a circular formation complementary to the opening 11 so as to be snugly fitted therein.

This main body part B is of a laminated construction and consists of a thin strip of material which is spirally wound so that the edges define the target surfaces of the main body part B. Such a strip of material as paper is shown at Figure 5, and identified by the reference character 12. The paper will have a required degree 40 of toughness and will be wound in its spiral arrangement fairly tight so as to insure of a compact solid structure in the body part B. However, there is just enough give between the layers of 45 the strip 12 to permit a point of a dart to be inserted therebetween.

At the center of the dart board, there is a ring element 13 (see Figure 4) which has each edge provided with a plurality of notches 14, and in 50 alignment with the notches 14 are corrugations 9 for a purpose to be hereinafter described. Received within the ring element 13 is a cork 15 which constitutes the center of the dart board in the usual manner. This ring 13 also serves as a 55 beginning for the spiral winding of the strip 12.

In accordance with the conventional practice 60 in this art to employ circular and radial markers for dividing the main body part up into various divisions, marking devices are included in the main body structure to mark off the target surfaces of the board in a manner following conventional practice.

Spaced inwardly from the outer periphery of 65 the main body part B, which is substantially coincident with the opening 11, is a ring element 16 of substantially the same width as the strip 12, and which ring element is preferably of metal whereby the edges of the strip are constituted a 70 circular marker. The edges of this strip are also

formed with a plurality of notches 17 which correspond to the notches 14 in the ring 13.

Radial markers take the form of metal wires 18 which are imbedded in the grooves 19 that are cut in the target surface defined by the edges of the strip 12. These grooves 19 are in alignment with the notches 14 and the ring 13, and the notches 17 and ring 16. Thus, one of the wire elements 18 is designed to provide a marker on opposite target faces by being imbedded in the grooves 19 and notches 14 and 17 on each face, the markers on the opposite faces being integrally connected by that portion of the wire extending down within the corrugations 9 in the ring 13 as shown at 21. At the outer extremity the free 15 ends of the wire 18 extend down over the ring 16 to a central opening in which they are received, as indicated at 20. Thus, the wires 18 are firmly imbedded in the body structure and are substantially flush with the surface thereof. 20

Obviously as many of the radial markers 18 may be availed of as occasion demands, and more than the single circular marker 16 may be employed as circumstances warrant.

While the circular marker 16 is shown as aiding in marking off circular dimensions of the board, it is to be remembered that other means may be employed alone, or in conjunction with the circular marker 16, for this purpose. The invention has particularly in mind the use of paper strips of different colors. Thus the paper strip immediately within the circular marker 16 may be of one color which is continued for a required distance to identify one circular zone. Then another strip of another color may mark off still another circular division. 25

The main body part B is intended to be detachably secured in position in the opening 11. To this end the frame 10 is shown as carrying at one side a back piece 22 which may be anchored to the frame 10 by any appropriate fastening devices such as the fastening elements indicated at 23. With the main body part B positioned within the opening 11, and in engagement with the back piece 22, retaining members 24 are secured to the front face of the frame 10 as by the fastening elements shown at 25. These retaining members extend a short distance over the main body part B and hold the latter in place. 40 45

If, after continued usage, it is found desirable 50 to reverse the target face, which is accessible for use, the retaining members 24 may be swung back out of effective position to permit of the removal of the main body part B, whereupon the latter part may be turned over and again positioned. 55

Following conventional practice in the field of dart boards, that portion of the framework 10 immediately adjacent the edge of the opening 11 is divided up into radial divisions corresponding 60 to the radial markers 18, and each of these divisions is provided with numerical indicia in the manner indicated at Figure 1.

When a dart point strikes against the effective target surface of the main body part B it will enter between adjacent layers of the strip 12 so that upon its removal the main body part is left substantially undamaged and in the same condition prior to the imbedding of the dart. The presence of the metallic markers insures that the dart point does not take the position on a marking line as the metal will deflect to one side of the marker or the other. 65 70

A somewhat modified form of dart board is shown in Figures 7 to 10, inclusive. In this form 75

the main body part of the board is made up of a strip 26 which is folded back and forth on itself many times to define a laminated structure comparable to the main body part B. This strip 26 5 also may be of any appropriate material, preferably paper, and when folded in the manner illustrated the compactly arranged edges thereof define the target surface of the board. After being folded into a compact structure in the manner illustrated, the folds are preferably cut off, as indicated by the dotted lines in Figure 10, thus insuring of a more solid structure.

In order to maintain the strip 26 in its properly folded position, a metallic framework comprising parts 27 is shown as completely encompassing the rectangular body structure defined by the strip 26. The extremities of the parts 27 take the form of ears 28 which are connected by headed bolts 29 which have associated therewith 20 nuts 30. Obviously the nuts 30 may be tightened to tighten the framework about the body part defined by the folded strip 26.

To insure of the strip 26 maintaining its properly folded position, particularly after the folds 25 have been cut off, each of the turns of the strip 26 may be formed with openings 32, and the several openings align, as shown in Figure 10, when the turns of the strips are in a compactly assembled relationship.

30 The side pieces of the frame parts 27 are also formed with openings corresponding to the openings 32, and which are in alignment therewith. A wire element 31 is then passed through the aligned openings 32, in the manner shown in Figures 7, 8 and 9, to complete the assembly.

It is notable that each end of the wire 31 may be anchored to one of the frame parts 27 in any preferred manner, as by the fastening elements shown at 33, thus providing for a required degree of tautness in the wire 31.

40 When this type of dart board is availed of the markings may be placed on both faces which constitute the target surfaces, by being lithographed, printed or inscribed thereon in any desired manner, this being developed in Figure 7.

45 While preferred specific embodiments of the invention are hereinbefore set forth it is to be clearly understood that we are not to be limited to the exact constructions illustrated and described, because various modifications of these details may 50 be provided in putting the invention into practice within the purview of the appended claims.

We claim:

1. In a target, a main body part comprising a strip of paper spirally wound into a compact structure, spaced rings imbedded in said structure, the edges of said rings being notched, the 5 edges of said paper strip being formed with grooves in substantial alignment with said notches, and wire markers imbedded in said grooves and notches.

2. A target comprising a framework formed 10 with a circular opening, a laminated main body part received in said opening and consisting of a spirally wound paper strip the edges of which define the target surface of said main body part, inner and outer rings carried by said main body 15 part having edges substantially in the surfaces defined by the edges of said paper strips, radial grooves on the opposite surfaces defined by said paper strip, and wire markers in said grooves, the marker in one radial groove being integrally 20 connected with the marker in the corresponding groove in the opposite face.

3. A target comprising a framework formed with a circular opening, a laminated main body part received in said opening and consisting of 25 a spirally wound paper strip, the edges of which define the target surface of said main body part, inner and outer rings carried by said main body part having edges substantially in the surfaces defined by the edges of said paper strips, radial 30 grooves on the opposite surfaces defined by said paper strip, and wire markers in said grooves, the marker in one radial groove being integrally connected with the marker in the corresponding groove in the opposite face, said markers comprising pieces of wire which pass through the inner ring and have their free extremities anchored in an opening in the outer ring. 35

4. A target of the character described comprising a plurality of concentric ring-like target 40 areas formed by a plurality of edges of tightly and closely wound laminations of strip material, concentric divider strips laminated between adjacent ring-like target areas with the edges of said strips being arranged substantially flush with the surfaces of said target areas, radial grooves cut in said target area surfaces and through said dividing strips, and radial dividers embedded and anchored in said grooves. 45
